Henry Stutt,

By Bollinger & Block. Attorney.

UNITED STATES PATENT OFFICE.

HENRY STUTT, OF DAVENPORT, IOWA; LAURA M. STUTT EXECUTRIX OF SAID HENRY STUTT, DECEASED.

GRAIN SHOCKER.

Application filed April 9, 1921. Serial No. 459,941.

To all whom it may concern:

Be it known that I, HENRY STUTT, a citizen of the United States, residing at Davenport, in the county of Scott and State of Iowa, have invented certain new and useful Improvements in Grain Shockers, of which the following is a specification, reference being had therein to the accompanying drawings.

10 My invention relates to new and useful improvements in a grain shocker and has for its principal object the provision of a device adapted to travel with the harvester and binder to receive the bundles from the 15 platform to which they are delivered by the binder, and transfer them to the bundle basket from which they are discharged onto the ground.

Another object is the construction of the 20 device in such a manner that it may be operated to deliver the bundles to the bundle basket with the butt ends extending rearwardly so that they will engage the ground when discharged from said basket.

25 A further object resides in the provision of means whereby the bundles are delivered to the basket at an angle so that when deposited upon the ground there will be an air space at the bottom of the shock.

30 A still further object consists in the provision of yieldable means whereby the transfer device may yield when the bundles are being stacked in the basket so as to prevent undue jar and breakage.

35 With the above and other objects in view which will appear as the description proceeds, my invention consists in the novel details of construction and arrangement of parts described and illustrated in the following specification and claims and while I have illustrated and described the preferred embodiments of the invention, it will be understood that such changes may be made as will fall within the scope of the 45 appended claims.

In the drawings:

Figure 1 is a top plan.

Fig. 2 is an enlarged top plan of the reversing pan.

40 Fig. 3 is a side elevation, and

Fig. 4 is a plan showing the reversing pan in dumping position.

45 In the drawings, 1 indicates the outline of a harvester and binder of usual construction having a downwardly slanting dis-

charge table 2 extending from one side thereof. My improved device is adapted to travel with the harvester and binder and is mounted along that side having the table extending therefrom. It consists of a main frame 3 mounted on the rear wheels 4 and the front wheel or castor 5, said frame having connected at the rear end thereof, for operation in any well known manner, the bundle receiving basket 6. This bundle receiving basket has a central dividing partition which extends half way into the basket from the rear when the basket is in its upright position, and this partition separates the rear ends of the bundles, in the basket in such a manner that when the basket is dumped to discharge the bundles onto the ground, in the form of a shock, there will be a space between the bundles of substantially inverted V-shape to allow the circulation of air for curing or ripening purposes. This arrangement of the shock on the ground allows the grain to be harvested when slightly green and allowed to ripen while shocked.

50 An auxiliary frame 7 is hingedly connected to the main frame 3, at 8, and the opposite end is yieldingly connected to the main frame by the coiled springs 9. These coiled springs are received in openings in both the main and auxiliary frames and are connected thereto by means of the transversely extending pins 10. They also pass through vertically extending openings formed in the beam 11 which is received on and secured to the rear end of the main frame 3. Secured to the rear end of the auxiliary frame is a transversely extending rod bent at the center to form the oppositely inclined portions 12 and 13. The ends of the portions 12 and 13 are bent at substantially right angles to form arms 14 which engage the sides of the frame and receive fastening means for securing the rod to the frame. Pivotedly connected to the transversely extending rod is my improved transfer device or pan which is adapted to receive the bundles from the discharge table 2. This transferring device or pan is formed in two sections 15 and 16, each having an upwardly extending flange 17 formed on the outer edge. The inner edge of each section 15 and 16 is inclined longitudinally so that the rear end of each section is of less width than the forward edge, and the inner edge 55

of the section 16 is curved upwardly as shown at 18 and overlies the inner edge of the section 15 when the sections are in their normal or receiving position. The rear end 5 of each section 15 and 16 is curved to form an eye 19 through which the transversely extending rod passes for pivotally connecting the transfer device or pan to the auxiliary frame. Upwardly extending projections 10 are formed on or secured to the bottom of each of the sections 15 and 16 of the pan and are adapted to engage the bundles in such a manner as to hold them in the pan when transferring to the bundle receiving basket 6 in a manner to be later described.

A crank shaft 21 is rotatably connected adjacent the rear end of the auxiliary frame by means of the plates 22 and one end thereof is bent to form the handle 23. The crank portion of the shaft is adapted to operate between the guides 24 secured to the underside of the sections 15 and 16 of the pan or transfer device. By the operation of the crank shaft, the sections of the pan are raised or lowered as desired and when raised the free ends of the sections will be separated due to the oppositely inclined portions 12 and 13 of the transversely extending rod secured to the auxiliary frame. When separated the sections of the pan will straddle the central partition in the bundle receiving basket 6 and deliver the bundles to the basket on each side of the partition with the outer ends separated for the purpose previously described.

From the above, it is thought that the detail construction of my invention will be clearly understood.

As stated in the objects my device is 40 adapted to travel with the harvester and binder and receives the bundles from the inclined table and transfers them to the bundle receiving basket from which they are discharged, in the usual manner, into shocks 45 upon the ground. When the bundles of grain are delivered from the binder table to the transfer device or pan, the butt ends are foremost and when received in the bundle basket the butt ends should extend rearwardly so that when dumped from the basket the butt ends will be received on the ground. My pan or transfer device reverses 50 the bundles, when swung, so that the bundles are properly received in the basket with their butt ends extending rearwardly. From the binder table the bundles are discharged into the transfer pan in such a manner that one bundle is received on each section of the pan with the butt ends extending 55 forwardly.

With two bundles received in the pan the handle 23 of the crank shaft 21 is operated to rotate the shaft and this raises the pan with the bundles thereon, the bundles being 60 held in the pan during the swinging thereof

by the projections 20. The swinging of the pan will separate the free ends of the sections so that they will straddle the central partition of the bundle basket and deliver a bundle on each side of the partition with 70 the rear ends separated as previously described. The bundles will drop from the pan into the basket and the operation is then reversed to bring the pan into its original position to receive additional bundles. Any 75 desired number of bundles may be received in the basket 6 before the same is dumped, but it will be understood that there will be an equal number on each side of the central partition. The basket may be dumped in 80 any desired or well known manner and as the construction thereof forms no part of my present invention I have not thought it necessary to illustrate the same or describe it in detail. While I have described the 85 crank shaft 21 as being rotated by hand, it will be understood that it might be operated through various manual or automatic means to accomplish the same purpose. As the pan is lowered to its original position the longitudinal extending curved edge 18 of the section 16 will ride over the inner edge of the section 15 to properly position the sections with respect to one another. When 90 a number of bundles have been stacked in the basket 6 there will be considerable jar to the pan and the auxiliary frame when the pan is swung to discharge position. To overcome this jar and prevent breakage, I 95 provide the springs 9 which yieldingly connect the free end of the auxiliary frame to the main frame. When the swinging of the pan is stopped by contact with the bundles in the basket the free end of the auxiliary 100 frame will yield and place the springs under tension. After pressure is relieved, the springs will return the end of the frame to its normal position. It will be noted that the springs are connected to that end of the auxiliary frame to which the sections of the 105 pan are connected.

Having fully described my invention what I claim and desire to secure by Letters Patent is:

1. A shocking attachment for binders comprising a bundle receiving basket and a sectional vertically swinging member for transferring the bundles from the binder to the basket, the sections being separable laterally when swinging.

2. A shocking attachment for binders comprising a bundle receiving basket having a central partition, and a sectional vertically swinging member for transferring the bundles from the binder to the basket, the sections of the said member separating laterally upon swinging to deliver the bundles on each side of the central partition.

3. A shocking attachment for binders comprising a bundle receiving basket having 130

1. A shocking attachment for binders comprising a central partition, a sectional vertically swinging member for transferring the bundles from the binder to the basket, and means for swinging the member vertically and simultaneously separating the sections laterally for delivering bundles to each side of the partition. 10
2. A shocking attachment for binders comprising a bundle receiving basket, and means for transferring the bundles from the binder to the basket, said means comprising a frame adapted to travel with the binder, a sectional pan pivotally connected to the frame for receiving the bundles from the binder, and means carried by the frame for swinging the pan vertically and separating the sections laterally. 15
3. A shocking attachment for binders comprising a bundle receiving basket, and means for transferring the bundles from the binder to the basket, said means comprising a frame adapted to travel with the binder, a rod connected to the frame and bent to form oppositely inclined portions, a sectional pan pivotally connected to the rod, and means for swinging the pan, the oppositely inclined portions of the rod causing the sections of the pan to separate during the swinging movement thereof. 20
4. A shocking attachment for binders comprising a bundle receiving basket having a central partition therein, and means for transferring the bundles from the binder to the basket, said means comprising a frame adapted to travel with the binder, a rod connected to the frame and bent to form oppositely inclined portions, a sectional pan pivotally connected to the rod, and means for swinging the pan, the oppositely inclined portions of the rod causing the sections of the pan to separate during the swinging movement thereof due to the oppositely inclined portions of the rod. 25
5. A shocking attachment for binders comprising a bundle receiving basket having a central partition therein, and means for transferring the bundles from the binder to the basket, said means comprising a frame adapted to travel with the binder, a rod connected to the frame and bent to form oppositely inclined portions, a sectional pan pivotally connected to the rod, and means for swinging the pan, the oppositely inclined portions of the rod causing the sections of the pan to separate during the swinging movement thereof due to the oppositely inclined portions of the rod. 30
6. A shocking attachment for binders comprising a bundle receiving basket having a central partition therein, and means for transferring the bundles from the binder to the basket, said means comprising a frame adapted to travel with the binder, a rod connected to the frame and bent to form oppositely inclined portions, a sectional pan pivotally connected to the rod, and means for swinging the pan, the oppositely inclined portions of the rod causing the sections of the pan to separate during the swinging movement thereof to deliver the bundles on opposite sides of the partition in the basket. 35
7. A shocking attachment for binders comprising a bundle receiving basket and means for transferring the bundles from the binder to the basket, said means comprising a frame adapted to travel with the binder, an auxiliary frame yieldingly connected to the first mentioned frame, a pan pivotally connected to the auxiliary frame for receiving the bundles from the binder, and means for swinging the pan for delivering the bundles to the basket. 40
8. A shocking attachment for binders comprising a bundle receiving basket, and means for transferring the bundles from the binder to the basket, said means comprising a frame adapted to travel with the binder, an auxiliary frame hingedly connected at one end to the first mentioned frame and yieldingly connected at the opposite end to the first mentioned frame, a pan pivotally connected to the auxiliary frame for receiving the bundles from the binder, and means for swinging the pan for delivering the bundles to the basket. 45
9. A shocking attachment for binders comprising a bundle receiving basket, and means for transferring the bundles from the binder to the basket, said means comprising a frame adapted to travel with the binder, an auxiliary frame hingedly connected at its forward end to the first mentioned frame, springs yieldingly connecting the rear end of the auxiliary frame to the first mentioned frame, a pan pivotally connected to the rear end of the auxiliary frame for receiving the bundles from the binder, and means for swinging the pan for delivering the bundles to the basket. 50
10. A shocking attachment for binders comprising a bundle receiving basket, and means for transferring the bundles from the binder to the basket, said means comprising a frame adapted to travel with the binder, an auxiliary frame yieldingly connected to the first mentioned frame, a rod connected to the auxiliary frame and bent to form oppositely extending inclined portions, a sectional pan pivotally connected to the rod for receiving the bundles from the binder, and means for swinging the pan for delivering the bundles to the basket, the sections of the pan separating during the swinging movement thereof due to the oppositely inclined portions of the rod. 55
11. A shocking attachment for binders comprising a bundle receiving basket, and means for transferring the bundles from the binder to the basket, said means comprising a frame adapted to travel with the binder, an auxiliary frame yieldingly connected to the first mentioned frame, a rod connected to the auxiliary frame and bent to form oppositely extending inclined portions, a sectional pan pivotally connected to the rod for receiving the bundles from the binder, the inner longitudinal edge of one section of the pan normally overlapping the inner longitudinal edge of the opposite section, and means for swinging the pan for delivering the bundles to the basket, the sections of the pan separating during the swinging movement thereof due to the oppositely inclined portions of the rod. 60
12. A shocking attachment for binders comprising a bundle receiving basket, and means for transferring the bundles from the binder to the basket, said means comprising a frame adapted to travel with the binder, an auxiliary frame yieldingly connected to the first mentioned frame, a rod connected to the auxiliary frame and bent to form oppositely extending inclined portions, a sectional pan pivotally connected to the rod for receiving the bundles from the binder, the inner longitudinal edge of one section of the pan being curved upwardly and normally overlapping the inner longitudinal edge of the opposite section. 65

the opposite section, and means for swinging the pan for delivering the bundles to the basket, the sections of the pan separating during the swinging thereof due to the oppositely inclined portions of the rod.

13. A shocking attachment for binders comprising a bundle receiving basket, and means for transferring the bundles from the binder to the basket, said means comprising
- 10 a frame, a pan pivotally connected to the frame for vertical swinging movement and for receiving the bundles from the binder, guides secured to the pan, a crank rod turnably connected to the frame and operating in
- 15 the guides of the pan, and means for turning the crank rod for swinging the pan for delivering the bundles to the basket.

14. A shocking attachment for binders comprising a bundle receiving basket, and
- 20 means for transferring the bundles from the binder to the basket, said means comprising

a frame, a rod connected to the frame and bent to form oppositely extending inclined portions, a sectional pan pivotally connected to the rod for receiving the bundles from the binder, a guide-way secured to each section of the pan, a crank rod turnably mounted on the frame and extending through the guide-ways of the pan, and means for operating the crank rod for swinging the pan for de-
25 livering the bundles to the basket, the swing-
ing of the pan separating the sections there-
of due to the oppositely inclined portions
of the rod, and the guide-ways allowing free
movement of the sections with respect to the
28 crank rod.

In testimony whereof I hereunto affix my signature in the presence of two witnesses.
